[57] CLAIM

The ornamental design for a visor, as shown and described.

DESCRIPTION

FIG. 1 is a front elevational view of the visor;
FIG. 2 is a rear elevational view of the visor;
FIG. 3 is a bottom plan view of the visor;
FIG. 4 is a top plan view of the visor;
FIG. 5 is a front perspective view of the visor;
FIG. 6 is a right end elevational view of the visor; and
FIG. 7 is a left end elevational view of the visor.
The characteristic feature of this design resides in the visor extension handle and housing as illustrated in FIGS. 1, 5, and 7.

Fig. 1
